UNITED STATES PATENT OFFICE.

JACOB BEHEL, OF ROCKFORD, ILLINOIS.

IMPROVEMENT IN WHIFFLETREE-HOOKS.

Specification forming part of Letters Patent No. **146,121**, dated January 6, 1874; application filed April 18, 1873.

To all whom it may concern:

Be it known that I, JACOB BEHEL, of Rockford, in the county of Winnebago and State of Illinois, have invented certain improvements in the common devices employed on single-trees, double-trees, neck-yokes, &c., for their connection with the harness and team, and with each other, of which the following is a specification:

My invention relates to the connection of the above or similar devices with the woods employed, the object being to obtain a more secure fastening with a less reduction of the wood, at a less cost, and that will admit of an artistic finish in fine work.

In the drawings hereunto annexed, the Figures 1, 2, 3, and 4 are in perspective; and Fig. 5, a longitudinal vertical section.

Fig. 1 represents the metallic portion usually known as "cockeye," in which A represents the outer portion, and is of button form. To the button A is attached the shank B, which is connected to flange C, leaving sufficient length of shank B between button A and flange C to receive the tug of the harness. To the ends of flange C are connected the flanges D and E, all of which flanges are connected by a center plate, F, which is perforated, as at G.

In Fig. 2, H is an end portion of the wood single-tree, slotted to receive the center plate F of Fig. 1, and is fitted in such a manner that the flanges D and E will embrace its opposite sides firmly, and is driven in until the end of the wood comes in close contact with the end flange C, the wood being previously bored to correspond with the hole in the center plate F. The rivet I is then inserted and riveted to draw the wood firmly to the center plate. In the above I have represented the device with a safety-button, A, over which the tug is passed onto the shank B; but do not wish to confine myself to this particular form, as it is evident that any of the known or usual forms may be substituted—such as the established cockeye, hook S, or T-formed bars. I have also used a rivet, instead of which screws or bolts may

be used. The above form is more particularly designed for light carriages when greater artistic finish is desirable.

In Fig. 3, C, D, and E are the flanges with center plate, as at F, Fig. 1, and is fitted and secured in the wood K, as in Fig. 2. From the flange D projects a cockeye, L, in which is a ring, M, to receive the breast-strap of the harness. This modification is designed more especially for a neck-yoke, but is applicable to a single-tree for heavy work, and a hook or link, T, may be used instead of the ring M, and is also applicable to a double-tree to connect the single-tree thereto by means of a lapping or other equivalent device.

In Fig. 4, C, D, and E are the flanges with center plate, as at F, Fig. 1, and is fitted and secured in the wood N, as in Fig. 2. From the flange E projects a shank of the usual hook form, provided with a safety T-formed bar on its outer end; but other forms may be used. This modification is more especially designed for agricultural work, and is suitable for medium and heavy work.

In the modifications in Figs. 3 and 4, the end flange C may be omitted, when the cockeye L or hook-shank is connected only to either flange D or E. If, from the shrinkage of the wood, the parts become loose, they may be made tight by closing the edges of the flanges C D E when malleable.

In Fig. 1, I have represented the shank B connected to flange C, in Fig. 3 to flange D, and in Fig. 4 to flange E; but it is evident that these and other similar well-known devices for the same purpose may be connected to any one or more than one of the flanges C D E without in the least departing from the gist of my invention.

I claim as my invention—

A whiffletree-hook having a shank, constructed with center plate F and flanges D E C, substantially as described.

JACOB BEHEL.
